KNITTING PIN

Bernard George Lewis, Redditch, England

Application June 11, 1946, Serial No. 675,965
In Great Britain October 17, 1945

2 Claims. (Cl. 66—117)

1

This invention relates to knitting pins, needles and the like, made of metal or other material.

Usually knitting pins are provided with a knob or enlargement at the end remote from the point to provide a stop for preventing accidental removal of the stitches from that end of the pin. The knob has often been made of an ornamental character, formed separately, and secured in place on the end of the pin. It is known, however, to form the knob in one with the metal of the pin, the integrally formed knob being produced by the process of upsetting or bumping-up the end of the metal wire or rod in suitable tools. The integral knob produced in this way is usually finished at its maximum diameter of circular form co-axial with the pin, and is sometimes made cylindrical with a slightly domed end face and sometimes conical with a slightly convex end face.

Pins or needles finished with coaxial heads of circular form are free to roll when placed on a table, chair or the like, and this causes considerable inconvenience and annoyance to the user.

It is common practice in the trade to mark knitting pins and needles with characters, either embossed or in relief, which indicate the gauge or size of the pin and sometimes also other particulars such as the trade-mark or name of the manufacturer. These characters are generally formed on flats provided for the purpose on the pin itself. These flats and markings interfere with the smooth working of the stitches on that part of the pin near the head and make it desirable, if this interference is to be avoided, to employ, for work having a given number of stitches, longer pins than would be really necessary were it not for the flats and their markings near the heads.

It is an object of the present invention to provide knitting pins, needles and the like with heads which will prevent them from rolling.

A further object is to provide knitting pins, needles and the like with heads which not only will prevent them from rolling but which will afford suitable surfaces for carrying markings or characters indicating the gauge of the pin or other particulars.

It is a feature of the present invention that the head of the knitting pin, needle or the like is provided with flat faces of substantial area and on opposite sides of the head, these faces preferably being parallel. A pin or needle provided with a head having flats of substantial area will not roll on any surface upon which it is placed. Moreover, the flats on the head afford suitable

2

surfaces on which characters can be displayed so that the surface of the metal wire or rod of the pin from the point right up to the head may be left smooth or unbroken.

5 In order that the invention may be clearly understood, it will not be more fully described with reference to the embodiments shown in the accompanying drawings; wherein:

Figure 1 is a perspective view of the knitting pin.

10 Figures 2 and 3 are side elevations of the headed end of the knitting pin shown in Figure 1, these two views being taken at right angles to one another.

15 Figure 4 is an enlarged section taken on the line 4—4 of Figure 3 to show how the head is secured to the wire or rod of the pin.

Figure 5 is an enlarged sectional side elevation of a metal head before being forced on to the 20 end of the wire or rod of the pin.

Figures 6 and 7 are similar views to Figures 2 and 3 but show a modified form of head.

Figure 8 is a plan of Figure 6.

Referring particularly to Figs. 1, 2 and 3 of the 25 drawings, the knitting pin comprises a cylindrical rod or wire 1 pointed at one end and having a head 2 at the other end. The surface of the rod or wire 1 is smooth or unbroken throughout its length from the point to the head 2, and the

30 latter has two parallel flat front and rear surfaces 3 which are of substantial area and bounded by a flat rectangular inner end face 4 from which the rod or wire 1 projects, outwardly divergent flat side surfaces 5, and convex outer 35 end face 6 contiguous with the side surfaces 5 and which is flat in a transverse direction. The flat parallel surfaces 3 prevent the knitting pin rolling upon any surface on which it is placed, and either or both of said surfaces 3 may bear 40 characters, preferably in relief or embossed, such as the trade-mark of the manufacturer and the gauge or size number of rod or wire 1, as shown for example in Fig. 2.

The head 2 is preferably made as a separate 45 part and is formed with a recess or socket, extending into the body of the head from its inner end face 4, to receive and make a tight push or force fit on the unpointed end of the rod or wire 1 as shown in Fig. 4. The heads may be pro-

50 duced as die castings if they are of metal, or as pressure or injection mouldings if they are made of other materials such as thermo-plastic or thermo-setting substances, usually termed plastics. In the die or mould a plurality of the heads 55 may be produced simultaneously, complete with

the desired markings on the flat front and rear surfaces 3 and with the recess or socket for receiving the rod or wire 4. In this latter connection and in the case of a metal head the recess or socket in the head may be made with a very slight taper as shown in Fig. 5 so as to afford an interference fit when the head 2 is forced on to the rod or wire 4; this results in a very secure mounting. The die cast metal heads would be polished, to provide the necessary finish, before being attached each to its rod or wire.

The embodiment shown in Figs. 6, 7 and 8 of the drawings is generally similar to that shown in Figs. 1, 2 and 3, the only material difference being that the flat front and rear faces 3 of the head are of slightly different shape and are bounded by contiguous side and end faces 5^x and 6^x which are convex both longitudinally and transversely.

I claim:

1. A knitting pin comprising a cylindrical rod pointed at one end and having a head at the other end, said head having two flat parallel front and rear faces which are of substantial area, and being bounded at its end nearer the pointed end of the rod by a flat face from which said rod projects and which is of substantially the same area as the cross-section of the rod adjacent the head, at its sides by side faces which diverge away from the pointed end of the rod, and at its outer end by a face which is contiguous with the divergent side faces.

2. A knitting pin comprising a cylindrical rod pointed at one end and having a head at the other end, said head having two flat parallel front and rear faces which are of substantial area, and being bounded at its end nearer the pointed end of the rod by a flat face from which said rod projects, at its sides by transversely convex side faces which diverge away from the pointed end of the rod, and at its outer end by a laterally convex face which is contiguous with the divergent convex side faces.
